UNITED STATES PATENT OFFICE.

DAVID G. MELVILLE, OF MEDFORD, ASSIGNOR TO THE ROXBURY CARPET COMPANY, OF BOSTON, MASSACHUSETTS.

DESIGN FOR A CARPET.

SPECIFICATION forming part of Design No. 14,806, dated September 18, 1883.

Application filed August 13, 1883. Term of patent 3½ years.

To all whom it may concern:

Be it known that I, DAVID G. MELVILLE, of Medford, in the county of Middlesex and State of Massachusetts, have invented a new and original Design for a Carpet, of which the following is a specification.

The nature of my design is fully shown in the accompanying photographit illustration.

The design is composed of the floral and foliage ornamentation forming a tracery on a contrasting ground, as shown.

I claim—

The design for a carpet, substantially as shown and described.

In testimony whereof I have signed my name to this specification, in the presence of two subscribing witnesses, this 30th day of July, 1883.

DAVID G. MELVILLE.
